United States Patent Office.

EDWIN D. BRAINARD, OF ALBANY, NEW YORK.

Letters Patent No. 93,046, dated July 27, 1869.

IMPROVEMENT IN REFRIGERATORS.

The Schedule referred to in these Letters Patent and making part of the same.

To all whom it may concern:

Be it known that I, EDWIN D. BRAINARD, of Albany, in the county of Albany, and State of New York, have made an Improvement in Refrigerators; and I do hereby declare that the following is a full and exact description thereof, reference being had to the accompanying drawings, which form a part of this specification.

Figure 1 represents an outside view of my improved portable refrigerator.

Figure 2 is a vertical cross-section through the line *y y*, fig. 1.

Figure 3 is a horizontal section through the line *x x*, fig. 1.

Figure 4 is a detached perspective view of one of the separate end-pieces, containing an independent non-conducting air-compartment.

Similar letters indicate the same parts in all the drawings.

This invention relates to an improved portable refrigerator for domestic purposes; and

My improvement consists in constructing the body or frame of double wooden walls or casings, in such manner as to form independent and separate air-spaces or compartments in the sides, ends, and bottom of the refrigerator, in which the wooden body or frame is sheathed, both internally and externally, with a continuous and hermetically-sealed sheet-metal wrapper.

Domestic refrigerators are usually constructed of a wooden frame, which is boarded and painted on the outside, and lined on the inside with sheet-zinc, or other metal, the space between the outside wooden boarding and the inside metal lining being filled in or packed with powdered charcoal, sawdust, or other non-conducting substance, to exclude the heat of the atmosphere.

This mode of constructing refrigerators is very defective. The external air penetrates through the outside wooden casing into the packing, carrying along with it both heat and moisture. The moisture condenses against the colder metallic lining of the interior refrigerating-chamber, and the constant dampness produced within the frame of the refrigerator rots the wood and rusts the metal, causing leakage and decay, which destroy its usefulness in a comparatively short time.

In my improved refrigerator these defects of construction are entirely obviated.

The casings or walls are made wholly of unplanned boards, which are cut up into sets of pieces to match exactly, so that they are easily nailed together to form a box-like frame containing separate and independent air-spaces or compartments between the inner and outer walls or casings, in the sides, ends, and bottom of the refrigerator.

The wooden frame is completely protected from the destructive influence of the atmospheric air, and the moisture it contains by the application of an external, as well as an internal metal sheathing, as hereinafter described, and as shown clearly in the drawings.

To enable others to make and use the same, I will now proceed to describe my improvement.

The outside walls or casings *a a*, of the sides of the wooden frame, are cut longer than the inside casings *b b*, so that their ends shall project far enough to admit separate end-pieces, formed of outer casings *c c*, and inner casings *d d*, as seen in fig. 3.

The side casings *a a* and *b b* are boxed up a few inches apart, to form air-spaces or compartments 1 1 between them, and the end casings *c c* and *d d* are boxed up to form air-compartments 2 2 between them.

At the bottom an outer casing, *e*, is nailed upon the longer side casings *a a*, and an inner casing, *g*, joins the inner side casings *b b*, forming an air-compartment, 3, in the under side of the refrigerator.

The end-pieces, formed of the inner and outer casings *c c* and *d d*, are put together separately, as shown in fig. 4, and are fitted in place between the projecting ends of the outer side casings *a a*, up against the ends of the inner side casings *b b*, and the inner bottom casing *g*.

They are fastened with nails or screws through the projecting ends of the outer casings *a a* and outer bottom casing *e*.

The body or frame of the refrigerator having thus been made of sawed boards, cut to match and form a parallelogram, perfectly true in its sides and proportions, is sheathed both externally and internally with a continuous wrapper, *s s*, of galvanized sheet-iron, zinc, or other suitable metal.

The sheathing is made of several metal sheets, joined at the edges by a folding-machine, and soldered together, to seal the seams hermetically.

The wooden body or frame of the refrigerator is thus completely protected, the metal sheathing on the outside is impervious to the external air, and no moisture can penetrate, to produce dampness and quick destruction of the wood and metal by rust and rot.

The air-compartments 1, 2, 3, between the walls or casings, are, in fact, dead-air chambers, being separate compartments, in which the air cannot circulate, and these dead-air chambers are better non-conductors of heat than any kind of packing.

A refrigerator thus constructed is cheap, effective, and durable.

The ice-box and fixtures in the interior of the refrigerator may be made, as usual, in any manner desired, but the cover should also be lined with sheet-metal, as shown in the drawings.

I do not claim broadly the separate and independent air-chambers or compartments in the frame or body of the refrigerator; but having fully described my improvement in the mode of constructing refrigerators,

What I claim, and desire to secure by Letters Patent, is—

A refrigerator, having the frame or body constructed with double side casings *a* and *b*, end casings *c* and *d*,

and bottom casings *e* and *g*, enclosing dead-air chambers 1, 2, and 3, when said frame or body is sheathed both externally and internally with a continuous and hermetically-sealed sheet-metal wrapper, *s*, substantially as and for the purposes herein described.

EDWIN D. BRAINARD.
